UNITED STATES PATENT OFFICE

2,067,238

TRIMMER CONDENSER

Lawrence C. Johnson, Chicago, Ill.

Application February 26, 1936, Serial No. 65,751

4 Claims. (Cl. 175—41.5)

The present invention relates to electrical condensers, and is particularly concerned with the type of condenser which is known as a trimmer condenser and adapted to be used in electrical circuits where a relatively small adjustable condenser is necessary, as, for example, in a radio receiving set.

One of the objects of the invention is the provision of an improved trimmer condenser, all of the parts of which are adapted to be made by stamping or punching operations and in which the parts are so supported that the capacity of the condenser is not affected by the pull exerted upon the electrical connectors of the trimmer condenser by the leads which are attached thereto.

In the devices of the prior art, condensers of this type have been provided with one or more integral metal tongues punched out of the body of the uppermost condenser plate and riveted or otherwise secured to an insulating support.

The plate referred to was then supported adjacent the other or lower condenser plate by a pair of resilient arms which are integral extensions from the part of the plate which is used as an electrical connector.

In the devices of the prior art much of the body of the upper plate was removed to form these integral attaching tongues, and the remaining portion of the body of the plate adjacent the point of attachment was such that any pull exerted upon the connector was transmitted up through the spring arms to the upper connector plate, varying the tension of the spring arms which support the connector plate and varying the capacity of the condenser.

The adjustment of such trimmer condensers is so critical that even the pull of attaching leads on the connectors was sufficient to throw the trimmer condenser out of adjustment, due to the construction and arrangement of the supporting parts for the plates in the devices of the prior art.

One of the objects of the invention is the provision of an improved trimmer condenser in which the removable condenser plate is so supported that its adjustment cannot be affected by any force which might be applied to the connectors in the normal operation or use of the condenser.

Another object of the invention is the provision of an improved trimmer condenser in which the action of the movable condenser plate is wholly independent of any normal forces applied to the connector members which form an integral part of such condenser plates.

Another object and advantage of the invention is the provision of an improved trimmer condenser

arrangement which may be constructed very economically, due to the fact that all of the parts are made or assembled by punching, stamping or riveting operations.

Other objects and advantages of the invention will be apparent from the accompanying drawing and the following description, in which similar characters of reference indicate similar parts throughout the several views.

Referring to the single sheet of drawings,

Fig. 1 is a top plan view of a bank of trimmer condensers constructed according to the present invention and supported upon a strip of insulating fiber or "Bakelite";

Fig. 2 is an enlarged top plan view of a single trimmer condenser embodying the invention and having for its support a porcelain block;

Fig. 3 is a sectional view, taken on the plane of the line 3—3 of Fig. 2, looking in the direction of the arrows, showing the details of construction of the trimmer condenser of Fig. 2;

Fig. 4 is a rear plan view of a trimmer condenser constructed according to the present invention, taken from the bottom of Fig. 2;

Fig. 5 is a fragmentary sectional view taken on the plane of the line 5—5 of Fig. 4, looking in the direction of the arrows.

Referring to Figs. 1 and 2, it will be observed that the present condensers may be supplied in single units or in banks of condensers. Where banks of condensers are employed, the condenser plates are all supported upon a single strip of insulating material 10, each of the respective condenser units being indicated in its entirety by the numeral 11. In such case, the additional units are merely duplicates of the single units, and the construction shown in Fig. 1 differs from that of Fig. 2 only in the use of an elongated insulating supporting strip 10, instead of the porcelain block 12 used in Figs. 2 and 3.

The insulating block 12, which may comprise an insulating member of any suitable material, such as porcelain, is preferably substantially rectangular in plan and in elevation. It is provided with a pair of apertures 13, 14 extending from top to bottom and adapted to receive the rivets 15, 16.

The rivet 15 serves to support the fixed condenser plate 17, which is fixedly secured to the insulating member 12. This fixed condenser plate may comprise a sheet metal member having the substantially rectangular plate body 18, which is disposed above the insulating support 12. Plate body 18 has an aperture 19 for passing the rivet 15 which clamps it to the insulating mem-

- ber 12. It also has an aperture 20, which is enlarged so as to pass the screw bolt 21 without contact between the screw bolt and the lower or fixed plate 17.
- 5 The fixed plate 17 is bent downward at the point 22, extending across the edge of the insulating block 12, and it is formed with a depending connector formation comprising a tongue of metal 23, having a suitable aperture 24.
- 10 The shape and arrangement of such a connector is shown in greater detail with respect to the connector 25, having aperture 26, which forms a part of the upper removable condenser plate, and is shown in elevation in Fig. 4.
- 15 This connector tongue may have partially circular grooves 27 located opposite each other at the point of juncture between the connector tongue 25 or 23 and the body of the condenser plates so as to weaken the connector tongues 20 along a line between the grooves 27. This causes the connector tongues to bend along this line, rather than in the body of the connectors, where the stock is also quite narrow, due to the formation of the apertures 23 and 26.
- 25 In order to permit the two condenser plates to be brought very closely together, without electrical conducting contact, the rivet 15 also secures above the plate 17 a thin sheet of mica 28, which also has an aperture 29 for passing screw bolt 30 21, and an aperture for receiving the rivet 15, which clamps the mica 28 and plate 17 to the insulating support 12.
- The mica sheet 28 preferably extends far enough to cover the upper end of rivet 16 to 35 eliminate any possibility of contact between the upper plate and the rivet, and the mica sheet may be substantially rectangular in section, completely covering the fixed condenser plate 17.
- The screw bolt 21 may comprise a threaded 40 and headed metal member, the head 30 being adapted to engage the top of the movable condenser plate 31 to draw it into closer proximity to the fixed plate 17.
- The threaded shank 32 of the screw bolt 21 45 may be threaded into the body of the insulating member 12; that is, the bore 33 in the insulating member may be formed with threads, and this is the preferred mode of construction when the insulating member is made of "Bakelite" or a 50 fiber strip. Where a porcelain insulating member 12 is employed, as in Fig. 3, this porcelain block is preferably formed with a non-circular socket 34 communicating with the lower end of bore 33 and adapted to receive the non-circular 55 nut 35, such as an ordinary hexagonal nut. This nut is held against turning by the walls of the socket 34, and it forms the fixed threaded connection between the screw bolt 21 and the insulating block 12. In such case, the bore 33 is of 60 sufficient size to permit sliding movement of the threaded shank 32 in the bore, as the screw bolt progresses in the nut 35.
- The movable condenser plate 31 comprises a 65 sheet metal member, which is formed with a substantially rectangular body portion 36, having an enlarged centrally located aperture 37 for slidably passing the shank 32 of screw bolt 21. The movable condenser plate 31 differs from the simple rectangular form in having the partially 70 circular cut-outs or grooves 38, 39 at each end of the plate adjacent to and concentric with the heads of rivets 15 and 16. The rivets 15 and 16, having heads which project above the insulating plate 12, would otherwise come into contact with 75 the movable plate first, and the proximity of

these two irregular metal bodies or rivets to the movable flat plate 31 might otherwise completely change the characteristics of the adjustment of the condenser.

At the rear of the movable condenser plate 31 5 it is provided with a pair of resilient pintle extensions 40, 41, comprising integral strips of metal located one on each side of the cut-out 39, the cut-out in this case actually being an aperture with the circular end 42 straight opposite end 43, and 10 straight sides 44, 45.

These resilient pintle extensions are preferably bent upward in partially cylindrical form so as to resiliently support the plate 31 and to urge the plate 31 upward into engagement with the head 30 15 of screw bolt 21.

The pintle extensions 40, 41 have their ends integrally joined to an attaching flange portion 46 which extends downward at right angles to the plane of the face of the insulating block 12. 20 The attaching portion 46 carries the integral connector formation 25 having the aperture 26, and has the opposite slots 27 to weaken the connector at the point of juncture and facilitate bending, as described. 25

Both the condenser plates 17 and 31 and the parts integral therewith are constructed of relatively thin resilient sheet metal which has a tendency toward flexibility, and the movable condenser plate 31 is preferably supported on the 30 insulating block 12 by a bracket 47 of thicker and stiffer material.

The bracket 47 may comprise a sheet metal member of relatively stiff stock, having an attaching flange 48, which may be of substantially 35 triangular form, as shown in Fig. 5. Attaching flange 48 has an aperture 49 for passing the rivet 16, which also passes through the bore 14 in the insulating member 12 and clamps the attaching flange 48 of bracket 47 fixedly to the insulating 40 block 12.

The attaching flange 48 supports the upwardly extending body portion 50 of the bracket 47, which body portion is at right angles to the attaching flange 48, and which lies against the flat 45 rear edge of the block 12. The flat engagement between the rear edge 51 of the block and the forward face of the body portion 50 of the bracket 47 serves to prevent rotation on the rivet 16, and the single rivet 16 secures this bracket to the insulating member and prevents all movement 50 thereof.

The bracket 47 is provided with a pair of clamping fingers 52, 53, which preferably are located in slots 54, 55, respectively, in the attaching flange 55 portion 46 of the movable condenser plate 31.

These clamping fingers 52, 53 preferably fit quite closely in the slots 54, 55, thereby preventing any vertical movement, in Fig. 4, of the attaching flange portion 46 with respect to the clamping 60 fingers 52, 53. The clamping fingers 52, 53 extend around the edge of the portion 46, and are bent into substantially U shape against the rear side of the flange portion 46. Since the fingers 52, 53 extend in opposite directions toward each other, they effectively and permanently secure the portion 46 of the condenser plate 31 to the bracket 47. 65

The attaching flange 48 of the bracket 47 is 70 preferably arranged under the insulating member 12 so as to prevent interference between this flange 48 and the upper condenser plate 31, to which it would be adjacent if it were on the upper side.

Another reason for placing the attaching flange 75

48 on the lower side of the insulating block 12 is to locate the point of attachment of the bracket to the insulating block closer to the connector 25 so as to be able to resist any lateral pull on the connector 25, such as that shown by the arrow P (Fig. 3), without transmitting force through the flange portion 46, to the resilient pintles 40.

It is found that the adjustment characteristics of trimmer condensers constructed according to 10 the present invention do not vary due to the action of the pull of any lead on a connector.

In some embodiments of the invention the bracket 47 may also be employed for securing the fixed condenser plate 17 to the opposite edge of 15 the insulating block 12, but the embodiment illustrated is preferred, as the single rivet attachment for the fixed plate 17 appears to be adequate.

While I have illustrated a preferred embodiment of my invention, many modifications may be 20 made without departing from the spirit of the invention, and I do not wish to be limited to the precise details of construction set forth, but desire to avail myself of all changes within the 25 scope of the appended claims.

Having thus described my invention, what I claim as new and desire to secure by Letters Patent of the United States, is:

1. In a trimmer condenser, the combination of 30 an insulating supporting plate with a fixed condenser plate comprising a sheet metal member having a flat body and a flat connector flange extending at right angles thereto, said insulating plate being of substantially rectangular shape in plan and elevation, and means for securing said flat body to one side of said insulating plate with said connector flange flatly engaging the edge of said plate, a movable condenser plate comprising a sheet metal member having a body portion similar in shape to the shape of the fixed condenser plate and connected to a supporting flange portion by a pair of spaced and resilient pinte 35 members, said securing flange portion extending at right angles to the body portion of said movable condenser plate and having a connector formation at its end and a bracket having a securing flange engaging the bottom of said insulating plate and secured thereto by securing means and having an upwardly extending flange engaging the edge of said insulating plate, and means for 40 securing said upwardly extending flange to the securing flange of said movable condenser plate.

2. In a trimmer condenser, the combination of 45 an insulating supporting plate with a fixed condenser plate comprising a sheet metal member having a flat body and a flat connector flange extending at right angles thereto, said insulating plate being of substantially rectangular shape in plan and elevation, means for securing said flat body to one side of said insulating plate with 50 said connector flange flatly engaging the edge of said plate, a movable condenser plate comprising a sheet metal member having a body portion similar in shape to the shape of the fixed condenser plate and connected to a supporting flange portion by a pair of spaced and resilient pinte 55 members, said securing flange portion extending at right angles to the body portion of said movable condenser plate and having a connector formation at its end and a bracket having a securing flange engaging the bottom of said insulating plate and secured thereto by securing means and having an upwardly extending flange engaging the edge of said insulating plate, means for securing said 60 upwardly extending flange to the securing flange of said movable condenser plate, comprising a pair of fingers carried by said upwardly extending flange extending about the securing flange of said movable condenser plate and clamping said securing flange to said vertically extending flange, said securing flange of said movable condenser plate having slots for reception of said fingers to determine the position of said securing flange within said fingers.

denser plate, comprising a pair of fingers carried by said upwardly extending flange extending about the securing flange of said movable condenser plate and clamping said securing flange to said vertically extending flange.

3. In a trimmer condenser, the combination of 5 an insulating supporting plate with a fixed condenser plate comprising a sheet metal member having a flat body and a flat connector flange extending at right angles thereto, said insulating plate being of substantially rectangular shape in plan and elevation, means for securing said flat body to one side of said insulating plate with said connector flange flatly engaging the edge of said plate, a movable condenser plate comprising a sheet metal member having a body portion similar in shape to the shape of the fixed condenser plate and connected to a supporting flange portion by a pair of spaced and resilient pinte 10 members, said securing flange portion extending at right angles to the body portion of said movable condenser plate and having a connector formation at its end and a bracket having a securing flange engaging the bottom of said insulating plate and secured thereto by securing means and having an upwardly extending flange engaging the edge of said insulating plate, and means for securing said upwardly extending flange to the securing flange of said movable condenser plate, comprising a pair of fingers carried by said upwardly extending flange extending about the securing flange of said movable condenser plate and clamping said securing flange to said vertically extending flange, 15 said securing flange of said movable condenser plate having slots for reception of said fingers to determine the position of said securing flange within said fingers.

4. In a trimmer condenser, the combination of 20 an insulating supporting plate with a fixed condenser plate comprising a sheet metal member having a flat body and a flat connector flange extending at right angles thereto, said insulating plate being of substantially rectangular shape in plan and elevation, means for securing said flat body to one side of said insulating plate with said connector flange flatly engaging the edge of said plate, a movable condenser plate comprising a sheet metal member having a body portion similar in shape to the shape of the fixed condenser 25 plate and connected to a supporting flange portion by a pair of spaced and resilient pinte members, said securing flange portion extending at right angles to the body portion of said movable condenser plate and having a connector formation at its end and a bracket having a securing flange engaging the bottom of said insulating plate and secured thereto by securing means and having an upwardly extending flange engaging the edge of said insulating plate, means for securing said 30 upwardly extending flange to the securing flange of said movable condenser plate, comprising a pair of fingers carried by said upwardly extending flange extending about the securing flange of said movable condenser plate and clamping said securing flange to said vertically extending flange, said securing flange of said movable condenser plate having slots for reception of said fingers to determine the position of said securing flange within said fingers, and threaded means 35 supported by said insulating plate and engaging said movable condenser plate to regulate the spacing of the condenser plates.
